J. DONOVAN

BAG HOLDER

Filed Feb. 13, 1924

UNITED STATES PATENT OFFICE.

JEROME DONOVAN, OF NEW YORK, N. Y.

BAG HOLDER.

Application filed February 13, 1924. Serial No. 692,548.

To all whom it may concern:

Be it known that I, JEROME DONOVAN, a citizen of the United States, residing at New York, in the county of New York and State of New York, have invented new and useful Improvements in Bag Holders, of which the following is a specification.

This invention relates to supports for bags and similar receptacles of the type comprising means adapted to maintain the bag open for the reception of refuse or other matter to be deposited therein.

An object of the invention is to provide a support which may be manufactured at inconsiderable cost, and which is particularly useful for the support of bags intended for the reception of refuse.

Another object of the invention is to afford a suspension bracket for a bag supporting loop ordinarily positioned in the mouth of a bag of a character which will permit the loop and bag to be supported in a plurality of positions and angularly adjusted in a vertical plane.

A further object of the invention is to provide improved means for securing the bag to its supporting loop, the means preferably being of a character which may be readily detached from the loop, and which has means for retaining a bag draw string.

A still further feature of the invention resides in the relative arrangement of the draw string retaining means with respect to the means for engaging the loop whereby, upon the tightening of the draw string, the bag may simultaneously be disengaged from its supporting loop.

Other and more minute features and objects of the invention are more closely related to the specific details of the construction, and will become clear as the description proceeds in connection with the embodiment of the invention illustrated in the accompanying drawings, wherein—

Fig. 1 is a perspective of one form of a device illustrating the invention,

Fig. 2 is a side elevational view with the suspension bracket shown partly in section,

Fig. 3 is a detail view showing the clips which are secured to the bag,

Fig. 4 is a fragmentary view of a modified form of the invention, and

Fig. 5 is a fragmentary view of another modification.

Referring to the drawings for a more detailed description, 10 indicates a device

which, in the present instance, is of annular shape adapted to fit into the mouth of a bag in order to maintain the bag open. This device, which, ordinarily, will be a loop, the shape of which may be modified as may be desired, has rigidly secured thereto a bail like member 11 having portions 12 of its side or arm sections inwardly turned and adapted to engage slots 13 in outwardly extending parallel arms 14 formed upon a suspension bracket 15. Extending between the arms 14 are members, such as vertically spaced bars 16, adapted to serve as stops to limit the upward movement of the end of the bail 11 when the loop is supported in either of the upper positions shown in Fig. 2. When the loop is supported in the horizontal position indicated in dotted lines, the bail may be placed beneath the lower bar or rod, or, if desired, the bail may be positioned so as to engage the under surface of the upper rod, as indicated in full lines. When not in use the loop and bail may be suspended in substantially vertical position, as indicated in Fig. 2. The bracket 15 is provided with suitable means, such as openings 17, whereby the same may be secured to any suitable rigid member, such as a wall or movable support, depending upon the purpose for which the bag support is to be employed.

It should be understood that the character of the bracket and of the means for securing the loop to the bracket may be materially modified without departing from the scope of the invention, since the essence of this feature of the invention resides in the provision of means whereby the loop may be adjusted in a vertical plane to a plurality of positions in accordance with the showing in Fig. 2, the means, of course, being of a character which will securely maintain the loop against accidental displacement and will suitably support the weight of the matter deposited in the bag.

The bag 18 may be of any suitable material, preferably non-inflammable, and should be detachably secured to the loop 10 so that the bag may be readily removed when full and another bag quickly placed in position. The securing means should preferably be of a character which will support a bag draw string so that when the full bag is removed its mouth may be closed. By reference to Fig. 2 it will be noted that the loop 10 has overturned flanges 19, 20 which cooperate

with clips 21 secured in spaced relation upon the edge of the bag. Each clip is formed from a strip of metal 22 bent upon itself at 23 and extending downwardly to form an 5 eye 24 and having its end 25 extending upwardly to close the eye. The edge of the bag is suitably connected to the clip as by a rivet 26 passing through the clip and bag material, and the clips are adapted to be en- 10 gaged beneath the flanges 19, 20 in the manner shown in Fig. 2. The eyes 24 serve as means for receiving the bag draw string 18' and for supporting the draw string in such a way that it may be drawn taut to close the 15 bag mouth with a minimum of resistance.

The clip construction disclosed may be readily modified within the scope of the invention; for instance, in Fig. 4 there is shown one modification of the invention in 20 which the loop 27 has an inwardly rolled upper edge 28 which is provided with a plurality of depressions 29 to form seats for clips 30 secured to the upper edge of a bag 18. The clips are provided with hook por- 25 tions 31 fitting over the upper edge of the loop in the seats 29 so that the clips are flush with the top surface of the loop. This permits a cover to be applied to the loop and to tightly seal the bag mouth while it is being maintained in position upon the support. The clips 30 have outwardly extending loop portions which form eyes 32 for the retention of the draw string and depending parallel portions 33 between which the bag 30 may be secured, as by means of rivets 34.

The structure shown in Fig. 5 is substantially similar to that shown in Fig. 4 with the exception that the draw string retaining eyes 35 are formed at the lower end of the 40 outer strip 36 of the clip, the clip being provided with hook portions 37 fitting over the upper edge of the loop. It will be observed that the eyes 35 upon the clip are positioned below the bottom edge of the loop 10', and 45 when the bag is to be removed it is simply necessary to pull the draw string taut whereupon the hooks 37 will be disengaged from the loop and at the same time the mouth of the bag closed.

50 It will be understood that the detailed disclosure in the foregoing description and accompanying drawings is given merely for the purpose of clearly setting forth the invention, and is in no sense restrictive of the 55 scope of the invention, the limits of which are to be determined by the prior art and by the following claims, wherein the invention is more definitely defined.

I claim:

60 1. In a device of the class described, a bag supporting loop, means for supporting the loop and means for securing a bag to said loop, said securing means comprising a plurality of devices each adapted to be secured to the bag and detachably to engage the loop 65

and support the bag and each having means for retaining a bag draw-string.

2. In a device of the class described, a bag supporting loop, means for supporting said loop permitting the loop to be angularly adjusted in a vertical plane, and means for securing a bag to said loop, said bag securing means comprising a plurality of clips adapted to be secured to the edge of the bag, 70 said clips each having means for detachably engaging said loop and supporting the bag and having an eye positioned upon the exterior of the bag through which a bag draw-string may be passed.

3. In a device of the class described, a bag supporting loop having a pair of spaced flanges, means for supporting said loop, and means for securing a bag to said loop, said bag securing means comprising a plurality of clips each having means for securing the 80 clip to the edge of the bag, means for detachably engaging said flanges, and means for supporting a bag draw-string.

4. In a device of the class described and in combination, a bag supporting loop 90 adapted to be positioned in the mouth of a bag, a bag, means for supporting the loop and means for securing said bag to the loop, said securing means comprising a plurality of clips secured to the edge of the bag, each 95 of said clips having means detachably engaging the loop to support the bag and each having an eye through which the bag draw-string is passed.

5. In a device of the class described and in combination, a bag supporting loop adapted to be positioned in the mouth of a bag, a bag having a draw-string, means for supporting said loop, said bag supporting loop having spaced flanges, and means for securing the bag to said loop, said securing means comprising a plurality of clips secured to the edge of the bag and having means co-operating with the loop flanges for detachably securing the bag to the loop, and each 105 clip having an eye positioned upon the exterior of the bag through which the bag draw-string is passed.

6. In a device of the class described, a bag supporting loop, a bail extending outwardly 115 from said loop and supporting means comprising a bracket having outwardly projecting arms upon which said bail is adapted to rest, and means extending between said arms beneath which a portion of said bail is 120 adapted to be positioned to hold the loop in a horizontal plane.

7. In a device of the class described, a bag supporting loop, a bail extending outwardly from said loop and supporting means comprising a bracket having outwardly projecting arms provided with sockets in which said bail is adapted to rest, and means extending between said arms beneath which a portion of said bail is adapted to be posi- 125 130

tioned to hold the loop in a horizontal plane.

8. In a device of the class described, a bag supporting loop, a bail extending outwardly from the loop in substantially the same plane therewith, and supporting means comprising a bracket having outwardly projecting arms adapted to receive the bail, and vertically spaced means extending between said arms and beneath which a portion of said bail is adapted to be selectively positioned to maintain the said loop in the desired position.

9. In a device of the class described, a bag supporting loop, a bail extending outwardly from the loop in substantially the same plane therewith, and supporting means comprising a bracket having outwardly projecting arms provided with upwardly inclined sockets adapted to receive the bail, and vertically spaced means extending between said arms and beneath which a portion of said bail is adapted to be positioned to maintain the said loop in the desired position.

10. In a device of the class described, a bag carrying member, means for securing a bag to said member, arms extending from the member and a support having devices fitting beneath said arms to serve as seats therefor and means positioned rearwardly of said seats beneath which the arms extend.

11. In a device of the class described, a bag carrying member, means for securing a bag to said member, arms extending from the member and a support having devices fitting beneath said arms to serve as seats therefor and means positioned rearwardly of said seats beneath which the arms extend, said means including a plurality of superposed stops adapted to permit adjustment of the adjacent portions of said arms with the seats serving as fulcrums.

12. In a device of the class described, a bag carrying member, rigid arms extending outwardly from said member and a support having means adapted to fit over and under each of said arms at spaced points longitudinally thereof to maintain the arms in substantially horizontal position.

13. In a device of the class described, a bag carrying member, rigid arms extending outwardly from said member and a support having means adapted to fit over and under each of said arms at spaced points longitudinally thereof to maintain the arms in substantially horizontal position, said means permitting pivotal adjustment of the bag carrying member in a vertical plane.

14. In a device of the class described, a bag carrying member, rigid arms extending outwardly from said member and a support for the member having means adapted to afford seats for said arms and means spaced from said seats longitudinally of the arms beneath which they are adapted to fit to hold them in fixed position upon said seats.

15. In a device of the class described, a bag carrying member, rigid arms extending outwardly from said member and a support for the member having means adapted to afford seats for said arms and means spaced from said seats longitudinally of the arms beneath which they are adapted to fit to hold them in fixed position upon said seats, said last mentioned means comprising a plurality of spaced stops adapted to permit the arms and carrying member to be pivotally adjusted upon said seats.

In testimony whereof I have hereunto set my hand.

JEROME DONOVAN.
